GLENN S. RAVEN, OF WATERTOWN, NEW YORK.

LICENSE-NUMBER PLATE FOR AUTOMOBILES.

1,389,983.

Specification of Letters Patent.

Patented Sept. 6, 1921.

Application filed February 17, 1921. Serial No. 445,687.

To all whom it may concern:

Be it known that I, GLENN S. RAVEN, a citizen of the United States, residing at Watertown, in the county of Jefferson and State of New York, have invented certain new and useful Improvements in License-Number Plates for Automobiles, of which the following is a specification.

This invention relates to improvements in license number plates for automobiles, and has for its object to provide a plate of the character which bears permanent identification numbers or symbols, and which may be permanently assigned to a particular car. 10 A further object is to provide novel and simple periodical identification means, which may from time to time be renewed or replaced, for example, at intervals corresponding to the regular license periods. And a 15 further object is to generally improve, simplify, and cheapen the cost of the production of automobile number plates.

I attain these objects by the means set forth in the detailed description as follows, 20 and as illustrated by the accompanying drawing, in which—

Figure 1 is a face view of the license plate, to which my improvement is applied. Fig. 2 is a vertical cross-section, taken on line 30 A—A of Fig. 1. Figs. 3 and 4 are similar broken face views of the main plate, upon which are mounted slightly modified year plates. And Figs. 5 and 6 are edge views 35 of the corresponding year plates, shown in Figs. 3 and 4.

In the drawing, 2 represents the permanent number or license plate, which is preferably substantially rectangular, the several corners thereof having the usual perforations 2', for the insertion of attaching means, such as nails or wires. 2^a designates a plurality of slotted openings disposed near the upper and lower corners of the main plate, through which similar stronger fasteners 40 such as bolts 2^b may be inserted for attaching the plate to an automobile. The plate 2 preferably bears the permanent identification numbers or characters, which may be assigned permanently to a car, to the end 45 that, the particular car may always be identified, by the letters and figures stamped, embossed or otherwise permanently applied to said plate, as "AE246" (see Fig. 1), which denotes that the identification number is 50 246 of series AE. It is understood, however, that any other suitable numbers or 55 characters may be employed for designating the identification series, if desired. The permanent identification and series characters are not, however, of the essence of my invention. My improvement consists specifically of a novel and simple periodical identification plate, which will hereinafter be designated the year-plate 3. These plates 3 are preferably detachable, and are intended to be renewed at the regular or stated license periods, while the main plates 2, together with the permanent identification characters, may be carried by a car for several years without renewing or 60 changing. The year-plate 3 consists of a strip of sheet metal, the upper end portion 3' of which is broader than the lower end portion 3^a, for providing relatively prominent shoulders 3^b, and adjacent the upper 65 and lower ends the plate 3 is provided with horizontal slots 3^c, which preferably coincide with the corresponding slots 3^a of the plate 2. This provision is made so that the bolts 2^b, which are employed for securely 70 fastening the main plate to the vehicle, may also hold the year-plates 3 from accidental loss, or unauthorized detachment. In order 75 to conveniently apply the year-plates 3 to the main plates 2, the latter are provided adjacent the right hand permanent identification character, with parallel horizontal slits 2^d and 2^e, the said slits preferably corresponding in length to the breadth of the reduced lower end portions 3^a of the year- 80 plates. In order to facilitate the insertion 85 of the year-plate, the portion 2^f of the plate 2 lying between the slits 2^d and 2^e is preferably pressed or bent rearwardly, out of the general plane of the plate 2, sufficiently to 85 permit the reduced end 3^a of the year-plate to be inserted downwardly, first through the slit 2^d then across the front face of the offset portion 2^f, and finally through the slit 2^e, until the shoulders 3^b are stopped by the 90 top edge of the portion 2^f. By this construction and arrangement, the year plates all being preferably stamped or cut to the same size and shape, may be readily, quickly and interchangeably applied to the plates 2. 95 The upper and lower ends 3' and 3^a of the year-plates preferably extend a short distance above and below the top and bottom margins of the plate 2, and these may be left in that condition, or either or both of the 100 projecting ends may be folded and clenched upon the face of the plate 2, as shown in 105 110

Figs. 3 and 4, if desired. The year-plates preferably bear figures or numerals denoting the year for which the licenses have been paid, as 23, shown in Figs. 1, 3 and 4, which stand for 1923. In practice, my year-plates 5 are prepared in advance for one or more years, and it is only necessary for the owner of a car, when applying for a renewal of his license, to assure the State authorities that 10 he still has the permanent plate 2, which contains the record identification characters, and upon payment of the license fee, the State will issue to him a new year-plate bearing the number (as 23) corresponding 15 to the new year. In the preferred form, my permanent identification plates 2, also bear the name of the state by which the license is granted, as NY for New York, OHIO, and PENN or PA for Pennsylvania, 20 and so on.

The permanent plates 2 should be made of relatively heavy and durable metal, which will last for a number of years, and the year-plates 3 should be made of a material 25 and gage that will insure at least a full year's life. By the provision, of the year-plates 3 constructed and arranged, as herein shown and described, the renewal of automobile licenses from year to year may be 30 effected at a relatively low cost to the State, as well as to the owners of the cars. The applying and removing of my year-plates 3 consumes but a few minutes' time, and may be accomplished without requiring the 35 removal of the permanent plates 2, or any alteration or change in either the permanent or removable plates.

Having thus described my invention, what I claim, is—

40 1. The combination with the main license plate having spaced horizontal slits near one end, of a detachable year-plate which bears a year number, said year-plate having its lower end portion reduced in breadth corresponding to the length of said slits, and 45 the upper end portion thereof being broader than said slits and provided with shoulders which align with the uppermost slit in the main plate, the said shoulders resting upon 50 the metal of the main plate lying between said slits.

2. The combination with the main number plate, bearing permanent identification characters, and having parallel slits beyond said characters, of a detachable plate bearing 55 characters denoting the year for which a license is granted, said detachable plate having a relatively broad upper end and a narrower lower end, and having oppositely facing shoulders which socket against the portions of the permanent plate adjacent the ends of one of said slits, and means for preventing the accidental detachment of the year-plate.

3. The combination with the permanent 65 license plate, said plate having spaced horizontal slits outside of the field of the permanent identification characters, and the metal of said plate lying between said slits being bent backwardly and means for securing said plate to an automobile, of a year plate having its longitudinal axis in vertical plane, the lower half of said year plate having a breadth substantially equal to the length of said slits adapted to be 70 inserted through the slits for exposing a portion which bears a year number, the upper half of said plate being broader for providing lateral shoulders which engage the top surface of the bent portion of the 75 permanent plate adjacent the uppermost slit, and having top and bottom openings to receive said securing means.

4. A license plate comprising a main plate having spaced horizontal slits near one end, 85 and slots above and below said slits a detachable year-plate, having a length substantially equal to the breadth of the main plate, and having its lowermost portion reduced in width corresponding to the length 90 of said slits adapted to be passed downwardly through the said slits, said year-plate having lateral shoulders which project beyond the ends of one of said slits for preventing gravitation of said plate, 95 and having slots which coincide with the slots of the main plate for receiving the fastening parts which secure the main plate to the automobile.

In testimony whereof I affix my signature.

GLENN S. RAVEN.
